UNITED STATES PATENT OFFICE

CHARLES C. MEUTSCH, OF BUFFALO, NEW YORK

DEVICE FOR SPRAYING UPHOLSTERY

Application filed May 24, 1928. Serial No. 280,197.

This invention relates to a device for spraying upholstered furniture and more particularly to a system of pipes permanently concealed in the upholstery of furniture and having a series of ports through which a fluid, for the extermination of moths and the like, is forced and sprayed into the upholstery.

Upholstered furniture and particularly upholstered furniture which is covered with mo-hair is particularly subject to attacks of moths which destroy portions of the covering and necessitate recovering of the entire piece of furniture in view of the fact that it is difficult to match particular portions of the covering. Heretofore it has been attempted to spray furniture with a moth exterminating fluid from the exterior of the same. The moths, however, get into the breaks between the different upholstered surfaces and make it extremely difficult to reach them by a surface spraying. The present invention, therefore, proposes a system of pipes which are concealed within the upholstery and are provided with a series of ports the entire length of the same, whereby the moth exterminating fluid is sprayed into those parts of the furniture where the moths are most likely to lodge, and also completely spray the upholstery from the interior thereof, thereby permeating the entire upholstering with the fumes of the moth exterminating fluid and also retaining the fumes within the upholstering for a considerable length of time. By this means only an occasional spraying is required.

One of the objects of this invention is to provide a device of this character which is completely concealed within the upholstery when not in use and does not interfere with the comfortable use of the piece of furniture.

A further object is to provide such a device which can readily and quickly be brought into operative position and the

spraying of the furniture accomplished thoroughly and in a short time.

A further aim of this invention is to provide such a device which has a reservoir for the storage of the moth exterminating fluid and in which it is only necessary to create an air pressure on the top of the reservoir to force a part of the fluid contained therein through the pipe system to effect a spraying of the upholstering.

A still further purpose is to so organize and arrange the pipe system that the spray will be discharged at the places in the upholstering where the moths are most likely to lodge and lay their eggs.

Other aims are to provide a device which is light, compact and inexpensive and which can readily be installed in furniture of standard design without substantial alteration thereof.

In the accompanying drawings:

Figure 1 is a perspective view of the frame of an upholstered arm chair of the "over-stuffed" type and showing the manner in which the piping, reservoir and filling and pressure pipe is carried thereby.

Figure 2 is a longitudinal section through an upholstered chair of the type shown in Figure 1.

Figure 3 is a vertical transverse section taken on line 3-3, Figure 2 and showing parts of the upholstering broken away to disclose the pipe system and reservoir.

Figure 4 is a fragmentary horizontal section, taken on line 4-4 of Figure 3 and looking downwardly.

Figure 5 shows a pipe system, reservoir and filling nozzle therefor which forms a unit which is adapted to be placed in furniture which is completely upholstered and ready for shipment.

Figure 6 shows a pump which is adapted for use in connection with the present invention, this pump being actuated through movement derived from the person sitting down in

the chair for spraying a quantity of the moth exterminating fluid into the upholstering.

The present invention is shown as applied to an overstuffed arm chair which in general 5 comprises an upholstered spring supported seat 10; an upholstered back 11; and two upholstered arms 12, the upholstering being arranged to provide breaks 13 between the arms and the seat and a break 14 between the back 10 and the seat.

The chair frame which supports the upholstering and also carries the system of pipes and the reservoir of the present invention, as best shown in Figure 1, comprises two front 15 posts 15, 15; two rear posts 16, 16; a front rail 17, connecting the front posts; a back rail 18 connecting the lower ends of the back posts 16; side rails 19, 19, connecting the lower ends of the corresponding front and back posts; a back rail 20 connecting the upper ends of the back posts; a pair of arm rails 21, 21, connecting the upper ends of the corresponding front and back posts; upholstering rails 22, 22, connecting the corresponding front and 25 back posts and arranged between the arm rails 21 and the side rails 19 thereof; vertical bars 23, 23, extending between the upper and lower back rails 20 and 19; and a horizontal back upholstering rail 24 between the vertical bars 30 23.

The seat of the chair may be upholstered in any well-known manner, and as shown in Figures 2 and 3, webbing 25 is stretched between the lower front, side, and back rails 35 and is secured to the underside thereof. The webbing supports a group of springs 26 which are housed within a burlap casing 27 which casing is suitably secured at its edges to the webbing. This casing is covered in the usual 40 manner with a fibrous stuffing 28, such as moss, hair or the like and the stuffing is enclosed by the cover 29. The cover 29 for the seat, is secured at its front to the front rail 17 and at its sides to the side rails 19, as best shown 45 in Figure 3. At its rear the cover 29 extends down and is secured to the back rail 18. At its center, as best shown in Figure 2, an opening 30 is left in the central part of the cover 29, this opening receiving the storage reservoir 31 of the fluid system.

Across the back of the frame a piece of webbing 32 is stretched, which webbing supports the group of back springs 33. These back springs are enclosed by a burlap casing 55 34, which is secured at its edges to the back rails 18 and 20 and the vertical bars 23. This casing is covered by stuffing 35 and the stuffing is covered by the back cover 36. The back cover 36 is secured at its lower end to 60 the lower back rail 19 and extends over and is secured at its upper end to the rear side of the upper back rail 20. At its sides this back cover 36 is secured to the outer side of the vertical bars 23, as best shown in Figure 4. 65 The webbing 32 is covered by a piece of bur-

lap 37, and over this burlap is arranged a sheet 38 of felted material, this felted material being covered by the back cover 36 which is extended over the rear side of the back and is secured at its lower end to the lower back 70 rail 18.

Each of the arms, as best shown in Figures 3 and 4 is upholstered in the following manner:

On the upper side of the arm rails 21 is arranged a longitudinal row of springs 39 which are housed in a burlap casing 40. Between the arm rail 21 and the upholstering rail 22 a piece 41 of burlap is stretched and over this piece of burlap 41 and the burlap housing 40 80 for the springs is arranged a mass of stuffing 42, which is molded to conform to the desired shape of the arms. The stuffing is covered by the arm cover 43 which is secured at its lower ends to the side rail 19 and extends 85 completely around the arm. The stuffing 42 extends around the underside of the roll or bulge of the arm, and to prevent its inward displacement a piece of burlap 44 is secured to the arm rail 21 and at its lower end is secured to the inner side of the cover 43.

It will, therefore, be apparent that the above construction provides an upholstered chair which has an interior hollow compartment 45 in the back, an interior compartment 46 in each of the arms and the upholstering is arranged to provide the breaks 13 and 14 around the seat, which permits things to be inserted between the seat and the arms and the back, thereby completely concealing the 100 same within the breaks 13 and 14. The reservoir 31 which is adapted to contain a supply of the moth exterminating fluid sufficient for a number of sprays of the piece of furniture is secured to the front side of the lower back rail 18 by means of a strap 47. This reservoir includes a vertical cylindrical body which is closed at its upper and lower ends by heads 48 and 49. In the upper head 48 is screwed a short section of pipe 491, in the upper end of which is arranged a swivel elbow 50. Extending laterally from this swivel elbow 50 is a filling pipe 51 having an elbow 52 at its outer end, which elbow opens upwardly. 115

The filling pipe 51 is arranged to swing rearwardly into the break 14 between the back 11 and the seat 10 and be completely concealed within this break. When it is desired to either fill the reservoir 31 with the moth exterminating fluid or to create an air pressure in the upper part of the reservoir the person spraying the chair reaches in the break 14, pulls the filling pipe 51 out, and pours a suitable quantity of moth exterminating fluid into the reservoir through this filling pipe. She thereafter attaches a suitable air pump (not shown) to the filling elbow 52 and forces air into the upper end of the reservoir. Such a pump may be of a 125 130

size which can be conveniently and readily inserted into the break 14 and be stored there-in in a position in which it is completely concealed and does not in any way affect the 5 comfort of the chair.

A short section of pipe 53 is secured on each side of the reservoir 31 at the lower end thereof and each connects with a vertical pipe 54 which extends up through an opening 10 in the back upholstering rail 24, as best shown in Figure 1. At its upper end each of these vertical pipes 54 is connected to a horizontal rear pipe 55 which extends outwardly therefrom and is arranged in front 15 of the vertical bars 23. Each of these pipes 55 have a T-coupling 56 to which is secured a vertical pipe 57 which extends upwardly between the vertical bar 23 and the corresponding back post 16. The upper end of 20 this vertical pipe is closed by a cap 58. To the other end of each of the T-couplings 56 is secured a short section of pipe 59 which is connected by an elbow 60 with a longitudinal extending pipe 61, the outer end of 25 which is capped. These pipes 61 are arranged within the interior compartment 46 of the arms and the pipes 55 are arranged in the interior compartment 45 of the back. Each of the pipes 61 and 55 30 are provided on their upper and lower sides with a series of ports 62, which series extend the entire length of these pipes and permit the fluid under pressure in these pipes to escape therefrom in fine streams which completely 35 saturate the interior of the upholstering of both the arms and the back.

In a similar manner the vertical pipes 57 are provided on their front and rear sides with a series of ports which spray the moth 40 exterminating fluid into the break between the back and the arms, as best shown in Figure 4.

It will, therefore, be apparent that when an air pressure is created in the upper part of 45 the reservoir 31 the fluid is forced through the system of pipes just described and is sprayed into the interior of the arms and the back and is also sprayed in the break between the arms and the back. By 50 this means the fluid is sprayed at the places where moths are most likely to lodge, particularly in the breaks between the different parts of the upholstering. Moreover after being sprayed the fumes of the exterminating 55 fluid are retained within the upholstering for a very considerable length of time and only infrequent use of the device is therefore necessary to completely insure the extermination of moths from the piece 60 of furniture.

In Figure 5 is shown a modification of the invention, shown in Figures 1-4. In this modification a reservoir and piping system is 65 provided which is made and sold as a unit and is adapted to be inserted in upholstered

furniture which is already fabricated or in actual use. In this construction the reservoir 31^a is arranged horizontally and is of comparatively small diameter thereby permitting it to be readily inserted in the break 70

14 between the back and the seat of the chair. The filling pipe 51^a is similarly connected by an elbow swivel 50^a with a short pipe section 49^a communicating with the upper end of the reservoir 31^a, as in the preferred construction and swings in and out of the break 14 as described.

The pipes 55^a each connect with the end of the reservoir 31^a through inclined pipes 54^a arranged at the lower end thereof and at its outer end each pipe 55^a is connected by an elbow 60^a with the longitudinal pipe 61^a which extends along the corresponding arm. By this means a reservoir with a U-shaped system of piping is provided and the complete unit 80 can be inserted into the breaks 13 and 14 between the seat 10 and the back 11 and arms 12. The pipes 55^a and 61^a in this construction are provided with a series of ports which spray the moth exterminating fluid into the 85 respective break. The operation of this form of the invention is similar to the operation or system shown in the preferred form. In order to permit of adapting the pipe system to different sizes and types of furniture a 90 coupling 80 is provided in the pipe 55^a. By this means if this form the invention is being applied to davenport, one section of the pipe 55^a can be cut to the desired length and 95 coupled to the other section by means of the coupling 80.

If it is desired to provide means whereby the weight of a person sitting down in the chair will operate to cause a small amount of moth exterminating fluid to be sprayed into the upholstering, a small air pump 70 may be housed within the seat 10, the casing of this pump being secured in any suitable manner to the webbing 25 and the piston rod thereof may be secured to the underside of a burlap casing 27. The outlet 71 for this pump may be connected with the reservoir 31 by means of a flexible conduit 72 or in any other suitable manner. By this means whenever a person sits down in the chair he moves the piston rod of the pump 70 downwardly and creates a pressure in the upper part of the reservoir 31 which operates to force a small quantity of the moth exterminating fluid through the piping system and into the upholstering.

This pump is more particularly adapted for the form of the invention shown in Figures 1-4 inasmuch as it is necessary to build it into the chair or piece of furniture while it is being upholstered. It is obvious that while the present invention has been shown and described with reference to an over-stuffed arm chair that it is equally applicable to other types of furniture and may be 130

variously organized to suit different requirements without departing from the scope of the invention, as set forth in the appended claims.

5. As a whole this invention provides a very simple and inexpensive system of pipes whereby moth exterminating fluid can be effectively sprayed into the interior of the upholstering and thereby permeate the entire piece of furniture. It is also convenient to use and when not in use is completely concealed in the upholstering and does not in any way interfere with the comfort of the piece of furniture.

15. I claim as my invention:

1. In combination with an upholstered piece of furniture, a device of the character described comprising a U-shaped system of pipes extending along the back and arms of 20 the piece of furniture and means for forcing liquid insecticide into said pipes, said pipes being provided with a series of ports through which the liquid insecticide is sprayed against the upholstering.

25. 2. In combination with an upholstered piece of furniture, a device of the character described, comprising a liquid insecticide reservoir arranged adjacent the break between the seat and back of the piece of furniture, pipes communicating with said reservoir and extending along the back and arms of the piece of furniture, said pipes being concealed by the upholstering and being provided with a series of ports directed against concealed surfaces of said upholstering, and means for forcing the liquid insecticide in 35 said reservoir into said pipes.

30. 3. In combination with an upholstered piece of furniture, a device of the character described comprising a conduit concealed by the upholstering and having a series of ports adapted to direct sprays of liquid insecticide against concealed surfaces of said upholstering, and a swinging pipe communicating 40 with said conduit and adapted to conduct the liquid insecticide into said conduit, said pipe being movable to a concealed position in one of the breaks of the piece of furniture.

45. 4. In combination with an upholstered piece of furniture, a device of the character described comprising a concealed fluid reservoir arranged adjacent one of the breaks in the piece of furniture, a conduit concealed by said upholstering and communicating 50 with said reservoir, said conduit having a series of ports adapted to direct sprays of fluid against concealed surfaces of said upholstering, and a swinging filling pipe carried by said reservoir, said filling pipe being movable to a position in which it is concealed within said break.

55. 5. In combination with an upholstered piece of furniture, a device of the character described comprising a concealed fluid reservoir arranged adjacent one of the breaks of

the piece of furniture, a pipe system communicating with said reservoir, said pipe system extending around the base of the arms and around the back of the piece of furniture and being concealed by the upholstering 70 thereof and said pipe system being provided with a series of ports adapted to direct sprays of fluid against concealed surfaces of the upholstering and a swinging filling pipe carried by said reservoir and movable to a position in which it is concealed within said break.

6. In combination with an upholstered furniture frame, a device of the character described comprising a fluid reservoir carried by the frame, a pipe system carried by 80 the frame and communicating with said reservoir, said pipe system including horizontal rear pipes arranged in the back of the piece of furniture and side pipes connected with 85 said rear pipes and arranged within the arms, said pipes being provided with ports adapted to direct sprays of liquid insecticide against the interior surfaces of the upholstery and means for forcing the liquid insecticide in 90 said reservoir into said pipes.

7. In combination with an upholstered furniture frame, a device of the character described comprising a fluid reservoir carried by the frame, a pipe system carried by the frame and communicating with said reservoir, said pipe system including horizontal 95 rear pipes arranged in the back of the piece of furniture, said pipes connected with said rear pipes and arranged within the arms, and a vertical pipe extending upwardly in said back adjacent the break between said arms and said back, said pipes being provided with ports adapted to direct sprays of fluid against the interior surfaces of the upholstery and means for forcing the fluid in 100 said reservoir into said pipes.

8. In combination with an upholstered furniture frame, a fluid reservoir secured to the lower back rail, a pipe communicating 110 with the lower end of said reservoir on opposite sides thereof said pipes extending transversely and being arranged within the back, a longitudinal pipe connected with the outer end of each of said transverse pipes, 115 each of said longitudinal pipes being arranged within an arm of the piece of furniture, said pipes being provided with a series of ports adapted to direct sprays of fluid against the interior surfaces of said upholstery, a filling pipe and a swivel connection between said filling pipe and the upper end of said reservoir, said filling pipe being movable to a position where it is concealed within 120 the break between the back and the seat of the piece of furniture.

9. In combination with an upholstered piece of furniture, a fluid reservoir carried by said frame, a conduit communicating with said reservoir and having a plurality of ports 130

adapted to direct sprays of fluid against concealed surfaces of said upholstery, a pump arranged within said upholstery and operable by the weight of the person using the 5 piece of furniture and a conduit between said pump and said reservoir whereby the operation of said pump creates a pressure in said reservoir which forces fluid into said first named conduit.

10 In testimony whereof I hereby affix my signature.

CHARLES C. MEUTSCH.
